PIANO CASE

Winsor D. White, Jr., Blowing Rock, N.C., assignor to D. H. Baldwin Company, Cincinnati, Ohio, a corporation of Ohio

Filed Nov. 18, 1964, Ser. No. 82,681

Term of patent 14 years

(Cl. D56—9)

The figure is a perspective view of a piano case embodying my new design.

The side of the piano case not shown is the same as the side shown.

The partially shown conventional keyboard is continuous across the piano as indicated by the long dash dot lines.

I claim:

The ornamental design for a piano case, substantially as shown and described.
